ATTACHMENT FOR INSTALLING MAGNETOS ON GAS-ENGINES.

14,060.

Specification of Reissued Letters Patent. Reissued Feb. 8, 1916.

Original No. 1,107,374, dated August 18, 1914, Serial No. 797,482. Application for reissue filed April 22, 1915. Serial No. 23,256.

To all whom it may concern:

Be it known that I, WALTER G. SWIFT, a citizen of the United States, residing at Providence, in the county of Providence and 5 State of Rhode Island, have invented certain new and useful Improvements in Attachments for Installing Magnetos on Gas-Engines, of which the following is a specification.

10 My invention relates to an improved attachment for internal-combustion motors or gas-engines for connecting a magneto to be driven therefrom.

15 The object of my improvement is to provide a simple form of direct drive between the motor and magneto, so arranged and assembled that it can be applied to standard types of motors now in use without requiring any material change in the construction 20 thereof and without necessitating the drilling and tapping of additional holes in the engine castings or other machine work thereon.

25 My improved attachment is designed especially for the engines of "Ford" automobiles whereby a high-tension magneto can be connected thereto to provide an improved ignition system for the cylinders to increase the speed and power of the motor. I accomplish this purpose by substituting a novel and ingenious form of gear-housing section for the front plate or cover originally attached to the engine and employing therein two new gears adapted to be connected with 30 the gear already in place on the crank-shaft. The new gears can be applied without any machining or fitting and the supplementary gear-housing section is attached with the same fastening means originally used. Furthermore, the new parts are so designed and 35 arranged that they occupy practically the same space as the original ones and hence the timing mechanism and other connected parts can be used in their same positions without 40 substitution or alteration.

45 The invention is fully described in the following specification, illustrated by the accompanying drawings, in which like reference characters designate like parts.

50 In the drawings:—Figure 1 is a front view of a usual type of gas-engine showing my new device applied thereto and illustrat-

ing the gear-case or housing with the cover and timer-box removed; Fig. 2 is a plan view showing the gear-housing in section on 55 the line X—X of Fig. 1; Fig. 3 is a side view showing the method of supporting the magneto from the gear-housing.

Referring first to Fig. 1, C designates the cylinders of a gasoline engine of the "Ford" type and C' is the lower section of the crank-case supported therefrom by the bolts, e, e, etc. D is the crank-shaft supported in the front bearing d and carrying the usual spur gear E which drives the cam-shaft F. The 65 parts above named are common to the type of engine specified and as usually arranged the cam-shaft F carries a spur gear adapted to mesh with the gear E and inclosed by a case or housing on the front of the main engine 70 casting. The ignition system of this style of engine ordinarily consists of a set of four vibrating coils, one for each cylinder, current being supplied to the primaries of the coils by a low tension magneto of the inductor 75 type, in which the coils are stationary and the magnets, being built into the fly-wheel, constitute the rotating part of the magneto. The circuits through the primaries of the different vibrating coils are completed at the 80 proper time by means of a distributor mounted in operative relation with the timing shaft of the engine. Since in this system of ignition, the frequency of the magneto current supplied to the vibrating coils 85 varies from approximately 50 to 500 cycles per second, it has been found that it is impossible to adjust the vibrators to respond to such wide range of frequencies with the result that the engine operates in a more or 90 less irregular manner, and it has been demonstrated that the efficiency of the motor can be greatly increased by using a separate high-tension magneto of some approved type. As 95 before stated my improvement consists in providing a means for connecting the magneto to be driven from the cam-shaft and this is accomplished with a minimum number of new parts and without destroying the arrangement of the timing-mechanism 100 which is mounted on the front end of the cam-shaft. The usual timing-gear which meshes with the crank-shaft gear E to drive the cam-shaft F is located in a housing G

which forms a part of the main cylinder casting C, see Fig. 2. The housing G is covered by a front plate or section, called the timing-gear plate, which is formed with a cap 5 for the crank-shaft bearing d and is bolted in place against the finished face g of the housing G. The cam-shaft F projects through this plate and carries the commutator or timer which with my new arrangement is retained in its same relative location without alteration or disturbance of its structure or method of operation. In order to make it possible to utilize the commutator-mechanism as originally applied to the 15 motor, without cutting away the timing-gear housing or any part of the crank-case, I have devised a novel form of supplementary gear-housing which takes the place of the original front plate or cover and can be secured to the engine with the same bolts, except the 20 two vertical ones immediately to the left of the crank-shaft D and below the new timing-gear, on account of the diameter of this gear, the bottom flange of the gear-housing 25 is cut away at the points where these bolts come in the old plate that is removed. I also substitute a new form of gear for the original timing-gear and these two parts are practically all that is added except, of course, the magneto, and its driving-gear and coupling.

Referring particularly to Fig. 2, the new timing-gear H is constructed with an offset, overhanging rim h which has approximately 35 twice the width of face of the original gear. This adapts it to project outwardly beyond the face g of the main gear-housing G so that its teeth may be brought into mesh with the teeth of the magneto-gear J. This latter 40 gear must of necessity be located out beyond the face of the housing G, for otherwise the housing would have to be cut away at this point and this is to be avoided in order not to mutilate the main engine casting. It will 45 be noted that the gear H is mounted on f, which is an extension of the cam-shaft F, being held rotatively by the dowel pins f', f' and secured against a flange f² by a sleeved nut f³, these parts remaining as originally 50 provided so that no new fastening means are required for the gear.

When the commutator wiper k is replaced on the cam-shaft F, as shown in Fig. 2, the timer-case or box K must be located in the 55 same relative position as formerly in order that the contacts k', etc., may have their proper relation to the wiper. To provide for this I construct my new, supplementary gear-housing section L with its front wall 60 let in or recessed in circular form at l and this provides an interior, annular channel l' for the rim of the timing-gear H. The face l² of the recessed portion l is finished off to provide a bearing for the circular rim of the 65 timer-box K and I also form an annular

flange l³ on the front face of the housing-section which is adapted to surround the rim of the box K to centralize the latter with the axis of the cam-shaft F. For holding the timer-box in position I use the same spring-arm or clamp M originally employed and this is secured to the housing L by a bolt m, as shown in Fig. 3, with its ball-shaped end m' engaging a recess k² in the front of the box K, see also Fig. 2.

Referring again to Fig. 1, the new gear-housing section L is formed with a bearing cap L' corresponding to the one on the regular housing front-plate which it replaces, and is adapted to fit exactly to the front of 70 the main housing G to which it is secured by the original bolts g', g', etc. At its left-hand-side, as viewed in Fig. 1, the housing-section L is formed with an integral extension L² adapted to surround the magneto-gear J and provided with a rearwardly-extending bearing l⁴ for the magneto stud shaft o. The magneto O, which may be of any well known type, is secured on a shelf or table P which is supported from the housing-section L by means of the bolts p, p, see 75 Figs. 1 and 3. To steady the table I attach it to the crank-case of the engine by means of the laterally extending lugs, p', p', adapted to receive the bolts p², p² which 80 secure the lower crank-case section to the main engine casting. The main support for the table which carries the magneto will be the housing-section L, since the torque strain comes at this point. However, in order to 85 further support table, means are provided as already explained and after the installation of the magneto has been completed, shims are to be inserted beneath the extending lugs 90 p', p' and the crank case of the engine, until 95 100 105 the solid support is obtained when the bolts p², p² are tightened up. The magneto O is held in position on the table P by suitable dowel-pins p³, p³, and is secured by the usual strap R. The magneto shaft s is connected 110 to the stud-shaft o by a "Universal" or "Oldham" coupling S. The outer end of the stud-shaft o has a bearing in a sleeve t which is supported in a hub t' forming part 115 of a cover-plate T. The cover-plate T is fitted to the finished face l⁵ of the housing-section L and is secured thereto by suitable screws t², t², etc.

Referring to Figs. 1 and 2, it will be noted that the casting of the housing-section L is 120 cored out at l⁶ to provide an opening through which the rim of the timing-gear H projects to adapt its teeth to mesh with those of the magneto-gear J. Referring to Figs. 1 and 3, the housing-section L is provided 125 with a vertical, cylindrical extension l⁷ which serves as a breather-tube and oil-inlet and is adapted to receive the original cap or stopper l⁸. A felt washer l⁹, see Fig. 2, is fitted to the opening l¹⁰ of the housing-sec- 130

tion L through which the end of the cam-shaft F projects to prevent leakage of oil at this point; and when the housing-section and cover-plate T are bolted snugly in place 5 as described the whole forms an oil-tight casing which completely covers and protects all of the gears and bearings.

The principal object of my invention has been to provide means for installing a magneto or other firing device, in connection 10 with an engine of the type specified, at the same time retaining the installation of the old equipment, so that in case the new equipment should fail, the old can be cut 15 back into service in a few seconds time, thereby giving substantially a dual ignition system. If the engine were equipped with a double set of spark plugs, both systems could be wired up and operated either singly 20 or together. The fact that two different types of ignition systems are available discounts the possibility of being "stalled" on account of ignition. My new attachment can be applied without cutting away 25 or mutilating the main engine castings, and with the addition of but very few parts. These parts consist merely of three new 30 castings, the housing-section, cover and magneto-table, and only two new gears. One of these gears replaces the regular timing-gear so that it can be said that only one 35 gear is added to those already used on the engine. Other arrangements sometimes used for the same purpose require as many 40 as three new gears and hence my new device shows considerable simplification in this respect. The parts of my new attachment are so few in number and so simple 45 that they can be manufactured at a comparatively small cost and, besides they are much easier to install. It does not require 50 a machinist or expert mechanic to apply the improved attachment to the motor, but, as a matter of fact, with a few simple directions a novice can make the installation in a 55 comparatively short time. When the installation is completed a very simple, compact driving connection is made which performs its duty more efficiently and with less 60 liability of getting out of order than any other arrangement ever devised for the same purpose. Besides taking up much less space than other systems it requires fewer new parts and is thus less expensive to 65 manufacture and easier to install.

It will be understood that I do not herein claim broadly a system of gearing for connecting a magneto with an engine, but only the particular features of novelty of 70 my device which consist essentially in the ingenious construction and combination of the elements described. Slight modifications might be made in the form and arrangement of the parts without departing 75 from the spirit or scope of the invention.

Therefore without limiting myself to the exact embodiment shown and described, what I claim is:

1. In an attachment for installing magnetos on gas-engines of the "Ford" type, the combination with the main engine casting and the cam-shaft projecting therefrom, of a substitute timing-gear formed with an overhanging rim having an extended tooth-face and adapted to be mounted on the cam-shaft with the said overhanging rim projecting beyond the front face of the engine casting, a magneto-drive-gear arranged to mesh with the teeth on the projecting rim of the timing-gear, a gear-housing section 75 formed with an interior, annular recess arranged to receive the overhanging rim of the timing-gear and adapted to be bolted to the engine casting to inclose both gears, and a stud-shaft extending rearwardly from the magneto-gear through gear-housing section 80 to adapt it to be connected with the magneto.

2. In an attachment for gas-engines of the "Ford" type adapted to connect a magneto to be driven therefrom, the combination with the main engine casting and the cam-shaft mounted in bearings therein, of a substitute timing-gear formed with an overhanging rim having an extended tooth-face and adapted to be mounted on the end 90 of the cam-shaft with its rim projecting beyond the front face of the engine casting, a magneto-drive-gear arranged to mesh with the teeth on the projecting rim of the timing-gear, a stud-shaft for connecting the magneto to its drive-gear, and a gear-housing section fitted to the front of the engine casting and adapted to inclose both gears, 95 said housing-section formed with an annular channel adapted to receive the overhanging rim of the timing-gear and a recessed front wall set in from the gear-inclosing portion to allow the replacement of the commutator on the cam-shaft in its original 100 position without disturbing the relation of its parts.

3. In an attachment for installing magnetos on gas-engines of the "Ford" type, the combination with the main engine casting 115 and the cam-shaft projecting therefrom, of a substitute timing-gear formed with an overhanging rim having an extended tooth-face, and adapted to be mounted on the cam-shaft with the said overhanging rim projecting beyond the front face of the engine casting, a magneto-drive-gear arranged to mesh 120 with the teeth on the projecting rim of the timing-gear, a gear-housing section formed with an interior, annular recess arranged to receive the projecting rim of the timing-gear and adapted to be bolted to the engine casting to inclose both gears, a table bolted 125 to the gear-housing section and extending rearwardly therefrom, a magneto mounted 130

on said table, and means to connect the magneto to be operated from the drive-gear.

4. In a magneto driving-connection for "Ford" engines, the combination with the main engine casting and the cam-shaft projecting therefrom, of a substitute timing-gear formed with an overhanging rim having a tooth-face of substantially twice the width of the original gear which it replaces and adapted to be mounted on the projecting end of the cam-shaft with its overhanging rim extending beyond the front face of the engine casting, a magneto-drive-gear arranged in position outwardly from the front face of the engine casting to adapt it to mesh with the overhanging portion of the timing-gear, a stud-shaft driven from said magneto-gear, and a gear-housing section formed with a bearing for the stud-shaft and adapted to be bolted to the engine casting to inclose both gears.

5. In an attachment for gas-engines of the "Ford" type, the combination with a timing-gear formed with an overhanging rim having an extended tooth-face, of a gear-housing section adapted to be bolted to the front face of the engine casting and formed with a cap for the crank-shaft bearing, and an annular, interiorly recess adapted to receive an overhanging rim of the timing-gear an exteriorly-recessed wall for receiving the commutator an extension formed with a bearing for the magneto drive-shaft and a flange inclosure for the magneto drive-gear, and a plate fitted to the outside of the housing to cover the drive-gear.

6. In a device of the class described, the combination of an engine-frame, a driving shaft projected therefrom, a gear housing for said engine frame inclosing said driving shaft, said gear housing have a table detachably supported thereto and extending rearwardly away from the face of said gear housing, a magneto mounted on said table, a stud shaft mounted within said gear housing, gears within said housing arranged to connect said driving-shaft to said stud shaft and means for connecting said stud shaft to said magneto shaft.

50 7. In a device of the class described, the combination of an engine frame, a driving shaft projecting therefrom, a gear housing attached to said frame and inclosing said driving shaft, gears inclosed within said housing, a table supported by said housing, a magneto adapted to be mounted on said table and driven by said gears, and a cover plate for one of said gears.

60 8. In a device of the class described, the combination of an engine frame, a driving shaft projecting therefrom, a gear housing attached to said frame and inclosing said driving shaft, gears inclosed within said housing, a table having its main support on said housing and a secondary support on

said engine frame, a magneto adapted to be mounted on said table and driven by said gears and means for closing the front of said housing to cover said gears.

9. In combination, an internal combustion engine, a magneto for firing fuel in said engine, a housing adapted to be fastened to said engine, means for driving said magneto, a table detachably fastened to said housing, and adapted to carry said magneto said housing inclosing said driving means.

10. In combination, an internal combustion engine, means for firing fuel in said engine, a housing adapted to be fastened to said engine, means for driving said firing means from said engine, said housing serving to inclose said driving means and having a table fastened thereto and extending rearwardly therefrom, said table carrying said firing means.

85 11. In combination, an internal combustion engine, means for firing fuel in said engine, a housing adapted to be fastened to said engine, means for driving said firing means from said engine, said housing serving to inclose said driving means and having a table fastened thereto and extending rearwardly therefrom, said table adapted to be fastened at its extremity away from the housing, to the engine frame and to carry said firing means.

90 12. In combination, an internal combustion engine, two sets of means for firing fuel in said engine, a housing adapted to be fastened to said engine, means for driving 100 said sets of firing means from said engine, said housing serving to inclose the driving means of one of said firing means and having a table fastened thereto and extending rearwardly therefrom, said table carrying 105 one of said firing means, a portion of the second set of firing means being carried on the front of said housing.

13. In combination, an internal combustion engine and a plurality of means for firing fuel in said engine, a housing attached to said engine and supporting a table which carries one of said firing means, a shaft from said engine, extending into said housing and a shaft adapted to be connected to the firing means on said table and extending into said housing, means for driving the last mentioned shaft from the first, said first mentioned shaft also serving to operate a second firing means, whereby both 120 said firing means are driven at the proper speed to fire said engine.

110 14. In combination, an internal combustion engine, a magneto for firing the fuel in said engine cylinders, a reserve means 125 for firing the fuel including a commutating device, a housing adapted to be fastened to said engine, means for driving said magneto and said commutating device, means for putting oil into the crank-case of said en- 130

gine; breathing means for allowing air to pass freely back and forth to the interior of said engine crank-case, said housing carrying the magneto and commutating device, the oiling and breathing means and encompassing said driving means.

15. In combination, an internal combustion engine, a magneto for firing the fuel in said engine cylinders, a reserve means for 10 firing the fuel including a commutating device, a housing adapted to be fastened to said engine, means for driving said magneto and said commutating device, means for putting oil into the crank-case of said engine, breathing means for allowing air to 15 pass freely back and forth to the interior of said engine crank-case, a table detachably fastened to said housing for carrying said magneto, the said oiling means being 20 integral with the housing and carrying the

breathing means, said commutating device being carried on the frame of said housing, said housing inclosing said driving means.

16. In combination, an internal combustion engine, a magneto for firing fuel in 25 said engine, a housing adapted to be fastened to said engine, means for driving said magneto, said housing having a table attached thereto for carrying said magneto whereby the torque strain is taken by said 30 housing which incloses said magneto driving means and means associated with said table to provide a supplemental support therefor.

In testimony whereof, I have affixed my 35 signature in the presence of two witnesses.

WALTER G. SWIFT.
